By his Attorney John C. Seifert.

UNITED STATES PATENT OFFICE.

DAVID ROBERT COOPER, OF ULTIMO, NEAR SYDNEY, NEW SOUTH WALES, AUSTRALIA.

LAST.

Application filed March 14, 1925, Serial No. 15,472, and in Australia September 4, 1924.

This invention relates to improvements in and connected with lasts, and more particularly to lasts of the type that are adapted to be extended and contracted to permit them 5 to be readily and conveniently inserted into and removed from articles of footwear made thereon, thus economizing time and labor and minimizing damage to the boots or shoes in manufacturing operations.

10 A last according to the invention is specially durable in construction, and it comprises a fore part, a longitudinally movable heel part permanently connected to the fore part, a detachable intermediate part of 15 wedge formation and means for locking said parts to restrain them against independent movement when assembled and the last extended.

Rigidly secured in the fore part of the last 20 is the forward end of a connecting plate having its rear end slidably accommodated in a recess formed in the heel part. The heel part is movable on said connecting plate, within predetermined limits, to and 25 from the fore part to permit required contraction and extension of the last. After detachment of the intermediate part, the said heel part is pivotal on the connecting plate and when advanced towards the fore part it 30 is permitted to have a slight upward collapsing movement which facilitates the contraction of the last to permit ready removal from the footwear.

The replacement of the wedge-shaped intermediate part forces the heel part rearwardly from the fore part, and simultaneously imparts slight pivotal movement in the opposite direction to said heel part, thus extending the last in correct manner 40 when the assembled parts are positively locked in rigid interfitting position.

Associated with the last is a lasting block 45 having its upper surface appropriately shaped to support the footwear (not having the heel affixed) when the last is being extended therein, its purpose being to preclude damage being done to the footwear by the operation of extending the last.

Reference is had to the accompanying 50 drawings, wherein:—

Figure 1 is a perspective view of the improved last.

Figure 2 is a longitudinal section of the last as extended and with its components 55 locked together.

Figure 3 is a longitudinal section showing the last contracted following the removal of the intermediate part of wedge formation.

Figure 4 is a central vertical section of the intermediate wedge part detached from 60 the fore and heel parts.

Figure 5 is a perspective view of a modified form of the invention.

Figure 6 is an end view of the intermediate wedge part of the sectional last seen in 65 Figure 5.

Figure 7 is a fragmentary view in plan showing the sectional last with the intermediate part fitted in position.

Figure 8 is a longitudinal sectional view 70 illustrating a further modified form of last.

Figure 9 is an elevation showing a shoe in the course of manufacture with contained last supported by a lasting block.

Referring to Figures 1 to 4, the last comprises a fore part 2, a heel part 3 and a detachable intermediate part 4. A vertical recess 5 is formed centrally in the rear portion of the said fore part 2 to receive the forward end of a metal connecting plate 6, 80 which is rigidly affixed in position to the said fore part by pins or rivets 7.

The heel part 3, having a metal plate inset 8 therein to prevent damage to that section of the last by nails in heelng operations 85 is constructed with a recess 9 to freely accommodate the rear enlarged end of the connecting plate 6 wherein a longitudinal tapering slot 10 is formed. Passed transversely through the heel part 3 and through the 90 tapering slot 10 is a hinge pin 11 permanently connecting the said heel part with the plate 6 that is immovably secured at its forward end to the fore part 2 of the last. This means of connection allows the heel part, 95 after detachment of the intermediate part 4, to be slidably moved on said connecting plate to and from the fore part 2, the degree of longitudinal movement permitted in either direction being determined by the 100 length of the slot 10.

The pin 11 by passing freely through the tapering slot 10 also provides a pivotal connection between the heel part 3 and the connecting plate 6. The intermediate wedge part 4 having been removed from the extended last, the said pin is initially at the rear enlarged end of the slot, when the heel part 3 is capable of being conveniently advanced toward the fore part 2. As the said pin ap- 110

proaches the forward narrower end of the slot, the said heel part is capable of slight pivotal movement (predetermined by the depth of the recess 9 and the depth of the enlarged end of the connecting plate 6), such pivotal movement facilitating the removal of the contracted last from the article of footwear.

Replacement of said intermediate part 4 10 imparts rearward slidable movement to the heel part 3 on the connecting plate 6, causing the pin 11 to be moved to the enlarged end of the tapering slot 10. The heel part is then permitted slight pivotal movement in 15 the opposite direction to bring the assembled last parts in correct relationship, when the upper and lower edges of the rear end of said connecting plate bear against the metal plate 8 and the bottom of the recess 9, 20 respectively—see Figure 2.

The detachable intermediate part 4 of the last is substantially of inverted T-shape comprising a wedge-shaped stem or shank having at its upper end two opposite horizontal members 12 and 13, and provided with a metal reinforcing plate 12^a. A slot 14 is formed in the lower end of said wedge-shaped stem or shank to enable it to fit snugly over that portion of the connecting plate 30 6 disposed between the opposed faces of the fore and heel parts 2 and 3. Said connecting plate by fitting in said slot thus additionally serves to prevent lateral movement 35 of the intermediate part when the extended last is subjected to working stresses. The inner surfaces of the members 12 and 13 of the T-shaped intermediate part are shaped to closely abut against the fore and heel parts 2 and 3, respectively.

40 Fitted in a hole formed in the sole of the fore part 2 is a nut 15, and a plug 16 is then tightly driven into said hole. Bored through said fore part and the forward horizontal member 12 of the intermediate part 45 4 are registering holes 17 and 18 to receive a long screw 19 having at its outer end a butterfly head 20 to bear against a metal washer 21 seated in said member 12. When the screw is screwed into the fixed nut 15 the 50 components of the extended last are positively locked together, while permitting ready detachment of the intermediate part 4 when the last is to be contracted for removal from the article of footwear.

55 The heel part 3 has a metal lined hole 22 adapted to register with a hole 23 bored in the rear horizontal member 13 of the detachable intermediate part 4 and receive the usual jack-pin used in lasting operations.

60 The provision in a sectional last of an intermediate wedge-shaped part formed with oppositely disposed members adapted to abut closely against the faces of the fore and heel parts and reinforced with a metal plate as 65 described ensures said intermediate part and

the extended last having the necessary strength to satisfactorily withstand all the strains that are developed in shoe manufacturing operations. The junctioning corners 24 may be right-angled or given that curvature which in operation is found most desirable to prevent fracture of the last parts under conditions of rough usage, particularly when the last is being extended within a boot or shoe by forcing apart the fore and heel parts 2 and 3 by the action of the wedge-shaped member of the intermediate part 4. 70

According to the modified construction of last illustrated in Figures 5, 6 and 7, the intermediate part 4 is of dovetail formation. 75 It has its opposite faces 25 and 26 of substantially V-shape and designed to interfit the correspondingly shaped ends 27 and 28 of the fore part and heel parts, thus ensuring correct alignment of the last sections when assembled and extended. The screw 19 may be passed in approximately a horizontal plane through the three parts of the last to engage at its rear end a nut 15 fitted in the heel part to correctly lock together the components of the last when it is extended. The screw 19 may have its head 20 seated in a recess 29 formed at the instep portion of the fore part 2 of the last, and a cord 30 permanently connects the detachable intermediate part 4 with the heel part 3 to prevent its misplacement or loss in manufacturing operations. 80

85 Referring to Figure 8 illustrating a sectional last principally for use in the manufacture of children's footwear, when extended its components are restrained against independent movement by tapered dowels 21 on the horizontal members 12 and 13 of the T-shaped intermediate part 4 of the last, 90 which dowels fit into tapered holes 32 formed in the fore and heel parts 2 and 3, respectively, of the last.

95 I provide a lasting block 33 (see Figure 9) 100 preferably constructed of wood, faced with aluminium or other metal, but which may be of all-metal construction. This block has its upper surface curved at 34 and 35 to seat the sole and waist portions of a boot or shoe 105 in the course of manufacture, and a straight portion 36 to support the heel end of the article of footwear. Prior to the affixture of the heel, the article of footwear without adequate reinforcement is not adapted to 110 withstand excessive and suddenly applied stresses, such as might be caused in extending the last therein, but a lasting block 33 having its upper surface of the contour illustrated 115 enables the last to be conveniently extended by the wedge section of the intermediate part 4 without causing any damage to the article of footwear. 120

125 What I do claim is:—

1. A last comprising a fore part, a connecting plate secured to and extending rear- 130

- wardly from said fore part, said plate having a tapered slot at its rear end, a heel part having a recess slidably accommodating the slotted end of said connecting plate, a hinge pin on the heel part passing through said tapered slot and a detachable intermediate part slotted to fit over said connecting plate.
5. A last as in claim 1 and wherein the intermediate part is wedge-shaped to cause the hinge pin to engage the larger end of the 10 tapered slot in the connecting plate, when the last is extended.
3. A last, as in claim 1 and wherein, the intermediate part has oppositely arranged horizontal members to fit beneath and support the fore and heel parts respectively.
- 15

In testimony whereof I affix my signature.

DAVID ROBERT COOPER.
